BASE FOR REAR VIEW MIRROR

Robert R. Rossi, Audubon, N. J., assignor to Peerless Accessories Co., Mount Holly, N. J., a corporation of New Jersey

Application April 30, 1956, Serial No. 41,280

Term of patent 14 years

(Cl. D14—6)
